United States Patent Office.

GEORGE SIEBEN, OF NEWARK, NEW JERSEY, ASSIGNOR TO JAMES H. WHITE, OF SAME PLACE.

Design No. 3,845, dated February 8, 1870.

DESIGN FOR SATCHEL-FASTENING.

The Schedule referred to in these Letters Patent and making part of the same.

To all whom it may concern:

Be it known that I, GEORGE SIEBEN, of Newark, in the county of Essex, and State of New Jersey, have invented a new Design for a Satchel-Fastening; and I do hereby declare that the following is a full, clear, and exact description of the same, reference being had to the accompanying drawing, forming part of this specification, and in which—

Figure 1 is a face-view of the fastening included in my design;

Figure 2 is a profile of the same, perpendicular to fig. 1; and

Figure 3, a sectional view thereof, taken as indicated by the line $x x$, in fig. 1.

Similar letters of reference indicate corresponding parts.

The fastening, in its general outline or contour, is that of a flat hook, with a partially circular swell or extension, a , from its back edge, the face of said extension lying in the same plane as that of the body of the hook, and being chamfered off on its edge, in common with the edge of said body, as at b .

Mounted on the face of said extension, and in concentric relation with the latter, is a protuberance, c , of general circular form, and of slightly concave shape on its edges, as at d .

The face of said protuberance is rounded on its edge, as at e , and ornamented within such rounded edge by a circular bead, f , of angular shape in its transverse section, and from the inner edge of the base of which projects a central conical portion, g , terminating at top in a semi or partially globular excrescence, h , which projects above the general outside level or face of the whole protuberance c .

What I claim, and desire to secure by Letters Patent, is—

The design for a satchel-fastening, as shown and described.

GEORGE SIEBEN.
